UNITED STATES PATENT OFFICE.

EDWARD S. TESDELL, OF DES MOINES, IOWA.

FUEL-HEATER FOR INTERNAL-COMBUSTION ENGINES.

1,209,072.

Specification of Letters Patent. Patented Dec. 19, 1916.

Application filed February 28, 1916. Serial No. 31,050.

To all whom it may concern:

Be it known that I, EDWARD S. TESDELL, a citizen of the United States, and resident of Des Moines, in the county of Polk and State of Iowa, have invented a certain new and useful Fuel-Heater for Internal-Combustion Engines, of which the following is a specification.

The object of my invention is to provide a fuel heater for internal combustion engines of simple, durable and inexpensive construction.

A further object is to provide such a fuel heater including the elements of an electrical circuit having a resistance element, the parts being so arranged that the resistance element is in the path of fuel travel from the main fuel supply tank to the carburetor mixing chamber with the resistance element in the fuel and covered thereby.

A further object is to provide in such a device, a plurality of heating elements with means for including any number of them in an electrical circuit or circuits for regulating the degree of heat produced.

A further object is to provide in such a device exposed heating elements spaced from each other in a fuel chamber.

Still a further object is to provide such a device in which the heating elements are mounted in the float chamber of a carburetor, and the parts are so arranged that when the float drops below a certain predetermined point, the heating elements are cut out of the circuit or circuits.

My invention consists in the construction, arrangement and combination of the various parts of the device, whereby the objects contemplated are attained as hereinafter more fully set forth, pointed out in my claims and illustrated in the accompanying drawings, in which:

Figure 1 shows a vertical, sectional view of the float chamber of a carburetor equipped with a fuel heater embodying my invention, the mixing chamber being shown in side elevation. Fig. 2 shows a horizontal, sectional view taken on the line 2—2 of Fig. 1.

In the accompanying drawings, I have used the reference numeral 10 to indicate generally the mixing chamber of a carburetor. Adjacent thereto is a float chamber 11 in which is a valve 12 controlled by a float 13 which may be of suitable construction.

Leading to the lower portion of the float chamber 11 is a fuel supply tube 14. Formed

on the lower part of the chamber 11 is a valve seat 15 arranged to coact with the valve 12.

Suitably mounted in the lower part of the float chamber 11, preferably in such position as to be below the level of the fuel in the float chamber when the carburetor is in use, are resistance elements 16, 17, 18 and 19. These resistance elements or coils may be insulated from the walls of the float chamber in any suitable way.

Mounted in suitable insulation 20 in the wall of the float chamber is a binding post 21, having at its inner end a contact point 22. On the opposite side of the float chamber is a bracket 23 of insulating material to which is secured a spring 24 extending across the lower part of the insulating chamber and adapted to stand with its free end engaging the contact point 22. On the spring 24 is an insulating block 25 adapted to be engaged by the float 13 if the latter should drop to a certain predetermined position.

Mounted in suitable insulation in the wall of the float chamber are binding posts 26 and 27. The inner end of the binding post 26 is connected with the resistance elements 16 and 17 by a wire 28. The inner end of the post 27 is connected by a wire 29 with the resistance elements 18 and 19 and is kept from contact with the elements 16 and 17 by an insulating coat 30.

The resistance elements 16, 17, 18 and 19 are connected together at points substantially opposite their points of connection with the wires 28 and 29 by a wire 31 with the spring 24.

Suitably located is a source of electrical energy 32. A wire 33 leads from the battery or other source of energy 32 to the binding post 21. The wire 33 is in two parts connected by a switch 34. A wire 35 connects the source of energy 32 with the binding post 26. The wire 35 is in two parts connected by a switch 37. A shunt wire 38 connects the wire 35 with the post 27. The wire 38 is in two parts connected by a switch 39.

In the practical operation of my improved heating device, when the parts are installed and ready for use, by closing the switches 34 and 37 a circuit will be completed through the switch 37, the wire 35, post 26, wire 28, resistance elements 16 and 17, spring 24, post 21, switch 34 and wire 33. A circuit can be completed through the re-

sistance elements 18 and 19 by closing the switch 39, which permits the current to pass through the wire 38, the post 27, the wire 29, the elements 19 and 18, the wire 31, and 5 the other parts already referred to in describing the first circuit, excepting the post 26, the wire 28 and the resistance elements 16 and 17. It is, therefore, apparent that if the fuel should pass out of the lower 10 part of the float chamber 11 for any reason, then when the float 13 drops upon the insulation 25 it thereby breaks the main circuit and cuts out the resistance elements automatically.

15 The advantages of a device of the kind hereinbefore described are largely obvious from the foregoing description.

It will be seen that the amount of heat generated in the float chamber may be regulated by cutting out or including in the 20 circuit part of the resistance elements. The resistance elements are mounted inside the float chamber and preferably in the fuel to be heated, so that there is a minimum 25 loss of electrical energy in heating the fuel.

I have found by actual experiment that the fuel can be thoroughly heated with very little current. The circuit is automatically cut off if the fuel should for any reason 30 cease to flow.

I consider it an advantage to place the resistance elements within the fuel chamber on account of the fact that this makes it possible to heat the fuel with considerably less 35 current than is the case where the heating elements are placed outside the fuel chamber. Below the resistance elements is a frame 50 of insulating material. It may be noted that gasoline and similar oils are 40 non-conductors.

While the elements are placed in an ordinary float chamber they may be placed in an oil reservoir or the like having a float

or other automatic switch controlling means.

It will be understood that some changes may be made in the construction and arrangement of the parts of my improved fuel heater without departing from the essential features and purposes thereof, and 50 it is my intention to cover by this application any such changes which may be included within the scope of my claims.

I claim as my invention.

1. In a device of the class described, a 55 fuel chamber in combination with a means for heating fuel therein, comprising a plurality of resistance coils received within the lower portion of said fuel chamber, and substantially spaced from each other, and 60 means for including a source of electrical energy and said coils in a circuit, said coils being exposed whereby heat may be applied to the fuel in said chamber quickly and intensely over a large area. 65

2. In a device of the class described, a fuel chamber, in combination with a means for heating fuel therein, comprising a plurality of resistance coils received within the lower portion of said fuel chamber, and 70 substantially spaced from each other, and means for selectively connecting said coils in one or more circuits, as may be desired, with a source of electrical energy.

3. In a device of the class described, a 75 fuel chamber having a valve, and a float operatively connected therewith, a resistance element in said chamber, an electrical circuit including said element and including a spring contact, said spring contact 80 being so arranged as to break the circuit when the float lowers below a predetermined point.

Des Moines, Iowa, February 19, 1916.

EDWARD S. TESDELL.
